2,507,419

FOUNTAIN TOOTHBRUSH HAVING BUILT-
IN AIR PUMP FOR FEEDING DENTIFRICE
FROM RESERVOIR TO BRISTLES

Ludwig F. Perwas, New York, N. Y.

Application June 6, 1945, Serial No. 597,748

1 Claim. (Cl. 15—133)

1

My present invention, in its broad aspect, has reference to improvements in fountain tooth brushes, and is characterized by the provision of an improved dispensing brush head communicating with a dentifrice reservoir in the handle of the brush, and a control valve to be set to dispense dentifrice or refill with dentifrice, and to withdraw remaining dentifrice from the brush head, after a quantity has been deposited on the bristles, and wherein an improved gear pump is employed to create pressure in the dentifrice reservoir, or to withdraw air and create suction in the dentifrice reservoir, depending on whether dentifrice is to be expelled from, or drawn into the reservoir. My brush and cap are oval in cross section, and the cap fits flush with the handle to enclose the brush head, and I provide an improved latch for holding the cap in place. Furthermore, I provide an improved operating means for the gear pump in the form of a knurled nut and associated parts, and floating seating plates for insuring the proper operation of the gear pump, and novel and improved means for refilling the reservoir through the dentifrice passages in the brush head. My device is relatively simple, practical, and will not leak when not in use, and may be conveniently carried in the pocket, and there are no parts likely to get out of order or to become broken.

Other and equally important objects and advantages of my invention will be apparent from the following description and drawings, and it is pointed out that changes in form, size, shape, materials, and construction and arrangement of parts are permissible and within the purview of my broad inventive concept, and the scope of the appended claim.

In the drawings, wherein I have shown a preferred form of my invention—

Figure 1 is a longitudinal section;

Figure 2 is a longitudinal section with the device turned 90° from the position shown in Figure 1;

Figure 3 is an enlarged section showing the threaded bristle supporting disk and dentifrice channels as mounted in the brush head;

Figure 4 is a top plan view of the bristle supporting disk;

Figure 5 is a detail view of the control needle valve;

Figure 6 is an enlarged section showing the control valve in operating position, and the cap latching mechanism;

Figure 7 is a detail of the cap latching device, the cap as engaging flush with the handle, and the brush head shank;

Figure 8 is a sectional detail showing the gear pump, knurled nut and rod and operating nut, in position to discharge air into the dentifrice reservoir to create pressure;

2

Figure 9 is a section on the line 9—9 of Figure 1;

Figure 10 is a section on the line 10—10 of Figure 1;

Figure 11 is a section on the line 11—11 of Figure 10;

Figure 12 is a plan view of the cover over the gear pump compartment;

Figure 13 is a detail showing the knurled nut 10 for operating the rod to withdraw the same prior to operating the gear pump;

Figure 14 is a fragmentary sectional view of the head actuating nut.

In the drawings, wherein like characters of reference are used to designate like or similar parts:

The numeral 1 designates my brush head which is channeled as at 2 throughout a portion of its length and has threaded openings 3 in its bristle face, each of which is formed with an annular recess 4. A threaded, flanged, removable disk 5 is engaged in each opening 3 with the flange seating in the recess 4 to lie flush with the face of the brush. Each disk carries bristle tufts 6 and is provided with wrench recesses 7. Those disks at the channel 2 are provided with a port 8 communicating with the channel—see Figures 1, 2, 3 and 4. The brush head has a curved shank 9 through which the channel 2 leads, and the shank is threaded to receive thereon a beveled knurled nut 10. Adjacent the end of the shank is a threaded washer 11 adapted to engage threads in the cylindrical cavity 12 in the end 13 of the handle 14. A conical cap member 15 is annularly recessed to seat about and be cemented to the annular flange 16 on the end 13 of the handle, and the nut 10 extends through opening 17 in the sides thereof to be accessible for turning to adjust the position of the shank and head, or to remove the same.

The end of the shank 9 is beveled for a seat for the beveled end of a needle valve 18—see Figures 1, 2, 5 and 6. The needle valve has a by-pass opening 19 through the end and out the side below the collar 20. Extending into the cylindrical channel 2 of the end 13 is a beveled flange 21 forming a valve seat for the valve 18, and between the flange and collar 20 is a spring 22 which normally unseats the valve. As will hereinafter appear, the nut 10 is manipulated to slightly release or extend the brush head to permit full opening of the control valve when evacuating the channel 2 of dentifrice after the brush has been used or the like.

The diameter of the end 13 of the handle is less than that of the handle 14, and the shoulder 23 on the handle 14 is beveled, and the edge of the cap 24 being beveled fits down flush with the handle against the shoulder 23. At each side, the end 13 is provided with openings 24 com-

municating with central bores 25. In each opening is mounted a slidable plate 26, and each plate has a centrally located sleeve part 27, and an annular edge flange 28. The edge of the inner wall of the front end of the sleeve part 27 has an internally beveled inner flange 29. The back end of each sleeve seats in the opening 24, and a spring 30 presses against the end of the opening and a disk 31 in the sleeve bearing against a ball 32 to project the ball against the flange 29 and beyond the forward end of the sleeve, and to urge the plate 26 out of the cavity to the limit determined by screws 33 engaged with the end. Recesses or depressions 34a are formed in the cap 24' to be engaged by the balls 32 in the closed position of the cap shown in Figure 1, at which time the plates are pushed in against the springs 30. The balls constitute a novel latch, and when the cap is removed, as in Figure 6, the plates and balls are pressed out, the limit of outward movement of the plates being set by the screws 33.

The chamber 35 in the hollow handle 14 constitutes a dentifrice reservoir which fills and discharges or dispenses through the cavity 12 and channel 2 of the head. Mounted in the end of the handle is a pump casing 36 which is flanged as at 37 for attachment to the handle, and which has a hollow extension 38 formed with a threaded port 39 in its end communicating with the reservoir 35. Extending through a packing gland 40 back of the end of the extension is a threaded rod 41 with a pointed tip 42 which fits into the port 39, and which has a knurled nut 43 at its opposite end. The lower portion of the rod is somewhat enlarged as at 44 and is provided with side slots 45. A knurled nut 46 is mounted about the rod and has lugs 47 fitting in the slots—see Figure 13—and the rod 41 also has a removable pin 48—see Figures 2 and 8—the purposes of which will hereinafter appear. A gear pump comprising a large drive gear 49, a small driven pump gear 50, and another small driven pump gear 51 intergated with the large gear by an idler 52 to rotate in the opposite direction as gear 50 is mounted in the casing 36 with the respective gears 50, 51 and 52 rotating on pins 53 journaled in the end wall of the casing and in the floating plate 54—see Figure 1. Gear 49 is mounted on the tubular member 44 and has a recess 55 to be engaged by the pin 48 in the rod 41. The floating plate 54 has edge packing 56 and ports 57 back of gears 50 and 51 communicating with air passages 58 leading to the slots in the member 44. A second floating plate 59 is mounted below plate 54 and packing 61 is located between the two plates, and a spring 62 in depressions in plates 54 and 59 press the plates respectively against the gear pump and the knurled nut 46, between which and the plate 59 is packing 63 thereby to completely seal the air pump. Air passes upwardly to the forward side of pump gears 50 and 51 through ports 64 in plate 54 from about the side edges of plate 59, nut 46 and slots 45 in member 41 in the direction of the arrows in Figure 11. The knurled nut 43 seats in the opening in the cover 65 which is attached to the pump casing by screws 66. Packing 67 is carried on the underside of nut 43 to seal against the upper face of nut 46.

In operation, the knurled nut 46 is manipulated to release or extend the head 1 so that the control valve 18 will be loosened to permit withdrawal of any dentifrice in channel 2 after use. To fill

my reservoir 35 with dentifrice, the nut 46 is manipulated to feed out the rod 41 whereupon the threaded end is released from port 39 to the position shown in Figure 8, and at the same time the rod feeds out to dispose the knurled nut 43 in position to be grasped by the fingers. Knurled nut 43 is now rotated to actuate gear 49 which operates the gear pump to draw air through port 39 from the reservoir 35 whereupon the suction 10 created draws dentifrice into the reservoir through the head. To dispense or fed dentifrice to the brush, the nut 43 is rotated in the opposite direction to force air through the port 39 to create pressure therein to cause dentifrice to flow 15 through channel 2 to the bristles.

From the foregoing, it is believed that the operation and advantages of my invention will be apparent, but it is again emphasized that interpretation of the scope of my invention should 20 only be conclusive when made in the light of the subjoined claim.

I claim:

In a fountain toothbrush having a brushing means, the combination therein of a handle, a 25 dentifrice reservoir contained therein, conduit means placing said reservoir in communication with the brushing means whereby dentifrice may be supplied from said reservoir to the brushing means, an open-sided gear casing on said handle, 30 pump gearing rotatably mounted in said gear casing, a floating plate slidably mounted in the open side of said gear casing forming a closure therefor, a backing means on said handle, resilient means between said floating plate and backing 35 means forcing said floating plate against said pump gearing, an outlet passage connecting said gear casing to said reservoir whereby pressure created by said pump gearing in said gear casing determines the pressure acting on said dentifrice 40 in said reservoir, said passage having an internally threaded port, a manually-operable rod slidably and rotatably extending through said pump gearing into said passage, a threaded portion terminating one end of said rod whereby said 45 rod may be threaded into said port for closing the same, separable clutch means on said pump gearing and said rod whereby when said rod is axially slid from said port, said clutch means become operative to drive said pump gearing by 50 said rod, whereby rotation of said rod causes rotation of said pump gearing thereby creating a pressure differential between said reservoir and the brushing means for causing movement of the dentifrice between said reservoir and the brushing 55 means.
